FEED CONTROL

Loyd A. Ward, Jackson, Mich., assignor to
Tomkins-Johnson Company, Jackson, Mich., a
corporation of Michigan

Application December 6, 1940, Serial No. 368,781

7 Claims. (Cl. 188—94)

The present invention relates to structure for controlling the rate of movement of a resiliently moved member and more particularly to a feed control for machine tools.

In the automatic feeding of cutting tools, it is desirable for several reasons to employ compressed air. However, the resiliency of a compressed air feed is undesirable in many cases, as for instance, in the pneumatic feeding of a drill through a piece of work. As the drill passes completely through a piece of work, the release of cutting resistance results in the drill being suddenly projected ahead, frequently with destructive consequences. According to the present invention, a pneumatic feed for machine tools is under the control of a hydraulic cylinder and piston, attention being given to providing a slow feed and quick return, as well as to providing multiple advancing speeds providing for rapid advance and slow feed over a single stroke.

An object of the invention is to provide a feed control comprising a resilient actuator and a hydraulic rate of movement control.

Another object of the invention is to provide a feed control comprising a pneumatic actuator and a hydraulic cylinder and piston rate of movement control.

Still another object of the invention is to provide a hydraulic feed control arranged to minimize interference of the control by air bubbles in the hydraulic fluid.

Still another object of the invention is to provide a hydraulic feed control consisting of a hydraulic cylinder and piston, having associated therewith a hydraulic fluid reservoir for maintaining the cylinder filled with hydraulic fluid during all stages of operation.

A further object of the invention is to provide a hydraulic control for a resilient feed, wherein a piston moves in a hydraulic chamber having a cylindrical cooperating portion, and a portion of larger diameter, whereby the piston may move freely in the chamber portion of larger diameter, but must move at a controlled rate in the cylindrical portion.

A still further object of the invention is to provide a hydraulic cylinder and piston feed control provided with a reservoir for maintaining the cylinder filled with hydraulic fluid, the reservoir having a connection with a source of compressed air for resiliently urging the hydraulic fluid from the reservoir into the cylinder.

These and other objects residing in the arrangement, combination and construction of the parts will be apparent from the following speci-

fication when taken with the accompanying drawings in which:

Fig. 1 is a plan view of a control according to the present invention,

5 Fig. 2 is a partial section on the line II—II of Fig. 1, the parts not in section being shown in elevation,

Fig. 3 is a plan view of another control according to the present invention,

10 Fig. 4 is a partial section on the line IV—IV of Fig. 3, the parts not in section being shown in elevation,

Fig. 5 is a reversed section on the line V—V of Fig. 3,

15 Fig. 6 is a section on the line VI—VI of Fig. 3,

Fig. 7 is an end elevation of another form of the invention,

Fig. 8 is a partial section on the line VIII—VIII of Fig. 7, the parts not in section being shown in

20 elevation,

Fig. 9 is an end elevation of still another form of the invention,

Fig. 10 is a partial section on the line X—X of Fig. 9, the parts not in section being shown in

25 elevation,

Fig. 11 is a partial section on the line XI—XI of Fig. 9, and

Fig. 12 is a section on the line XII—XII of Fig. 9.

30 In Figs. 1 and 2 of the drawings, there is disclosed one form of the invention for providing rapid advancing, slow feeding and rapid returning. The reference character 1 indicates a pneumatic cylinder having therein a piston 2 and a

35 piston rod 3. The piston 2 is actuated by suitable pneumatic controls, not shown, and the piston rod 3 is operatively connected to some mechanism to be actuated, as for instance, a machine tool.

40 For controlling the rate of movement of the piston rod 3, the piston 2 has connected thereto a piston rod 4, having on the outer end thereof a piston 5, the piston 5 being smaller in diameter than the piston 2. The piston 5 is disposed in a

45 hydraulic chamber 6. The chamber 6 is provided with a cylindrical portion 7 for cooperating with the piston 5 and an enlarged portion 8 in which the piston 5 is freely movable. Between the enlarged portion 8 and the cylindrical portion 7, the hydraulic chamber 6 is provided with a flared bell shaped portion 9.

The piston rod 4 extends through an end member 10 of the cylinder 1 and the end member 11 of the hydraulic chamber 6. As shown in Fig. 2, 55 the end members 10 and 11 are clamped together

by cap screws 12. Surrounding the piston rod 4 in the end member 10 is a packing ring 13, secured therein by a nut 14, and surrounding the piston rod 4 in the end member 11 are packing rings 15, secured therein by a nut 16.

Between the nuts 14 and 16 and disposed in the end member 11 is an annular recess 17, connected by a vent 18 to the atmosphere. Thus, any air leaking by the packing ring 13 from the pneumatic cylinder 1 or any hydraulic fluid leaking by the packing rings 15 from the hydraulic chamber 6 will be vented to the atmosphere and will prevent the entrance of any air from the pneumatic cylinder 1 into the hydraulic chamber 6.

Within the end member 11 of the hydraulic chamber 6 is disposed an annular space 22. The space 22 comprises an extension of the cylindrical portion 7 of the hydraulic chamber 6 and has communicating therewith a port 23. The port 23 has connected thereto a conduit 24 which is in turn connected to a valve 25, and the valve 25 is connected with the enlarged portion 8 of the hydraulic chamber 6.

The operation of the structure just described is as follows: The hydraulic chamber 6 is provided with a hydraulic fluid up to the level 26 for instance, leaving some suitable air space thereabove. As the piston 2 is moved downwardly in the pneumatic cylinder 1, the piston rod 4 moves downwardly moving with it the piston 5. Since the piston 5 freely moves in the hydraulic chamber 6, in the upper portions thereof, there will be no retarding of the rate of movement of the piston 2 until the piston 5 moves into cooperating relation with the cylindrical portion 7 of the hydraulic chamber 6. At this point the hydraulic fluid in the cylindrical portion 7 will be forced ahead of the piston 5 through the port 23, the conduit 24 and the valve 25, the valve 25 having been previously adjusted to restrict the passage of hydraulic fluid therethrough to such an extent as to provide the desired rate of movement of the piston 5 and consequently the piston 2.

As the piston 5 moves downwardly, a portion of the piston rod 4 moves out of the hydraulic chamber 6, thereby in effect increasing the effective space therein. The air in the space above the level of the hydraulic fluid expands by an amount equal to the volume of the piston 4 moved out of the hydraulic chamber 6 to thereby permit the relatively unhampered movement of the piston 5.

When the piston 2 has reached the lower extremity of its stroke and consequently the piston 5 likewise, the piston 2 is returned toward the position shown in Fig. 2, moving through the piston rod 4, the piston 5. As the piston 5 starts its return movement, enough hydraulic fluid flows back through the valve 25, the conduit 24 and the port 23 and past the piston 5 to permit the piston 5 to move upwardly through the cylindrical portion 7 to the outwardly flared portion 9, at which point the hydraulic fluid from above rushes in behind the piston 5, without materially slowing the return of the piston 2. The valve 25 should communicate with the hydraulic chamber 6 at a point which is always below the level of the hydraulic fluid therein, so that upon the return movement of the piston 5 no air will be drawn through the valve 25 and into the hydraulic fluid. The necessity for preventing air in the hydraulic fluid will be apparent when it is realized that any air bubbles therein which may be forced through the valve 25 on feeding or downward movement of the piston 5 will result in irregular

downward movement of the piston 5 and thus of the piston rod 3.

Another feature of the invention is that since the area of the piston 2 is greater than the area 5 of the piston 5, the pressure to which the hydraulic fluid in the cylindrical portion 7 is subjected after the piston 5 cooperates therewith will be greater than the pressure of the air in the pneumatic cylinder 1. Thus, any tendency of leakage past the piston rod 4 will be in a direction from the hydraulic chamber 6 rather than toward the same. This tendency will insure against any air from the pneumatic cylinder 1 leaking into the hydraulic chamber 6, although as a matter of fact, as pointed out above, the vent 18 is also provided for insuring against the leakage of air past the piston 4 into the hydraulic chamber 6. Another feature of the invention is that due to the increased pressure in the cylindrical portion 7 of the hydraulic chamber 6, any air bubbles that may accidentally get into the hydraulic fluid are compressed to such an extent that the effect of their passage through the valve 25 is minimized.

Figs. 3 through 6 disclose another form of the invention, wherein a feed control is provided for a vertically movable pneumatic cylinder and piston differing from the first part of the invention, however, in that the slow feed is effective throughout the entire forward movement of the pneumatic piston and the quick return is provided by the use of a check valve rather than by the construction of the hydraulic chamber. The pneumatic cylinder 1, together with its piston 2 and piston rod 3 are the same as in the first form of the invention and are for the same purpose. Likewise, the end member 10 for the cylinder 1 is the same. The end member 10 is secured by cap screws 12 to an end member 30 of a hydraulic cylinder 31. The end member 30 also serves as an end member for a reservoir cylinder 32 surrounding the cylinder 31. Disposed in the hydraulic cylinder 31 is a piston 33, similar to the piston 5. The pistons 2 and 33 are connected by 25 a piston rod 34, which is reciprocable in the end members 10 and 30, which respectively are provided with packing rings 13 and 15, held in place by nuts 14 and 16, as disclosed in Fig. 2. Also, an annular space 17 about the piston rod 34 is connected by a vent 18 to the atmosphere.

The end member 30 is provided with an annular space 35 comprising a continuation of the hydraulic cylinder 31. Communicating with the space 35 is a port 36 connected to a valve 37, which is in turn connected by a conduit 38 to the reservoir cylinder 32. The valve 37 constitutes a restricted adjustable orifice, similar to the valve 25 of Figs. 1 and 2.

A communication is provided between the hydraulic cylinder 31 and the reservoir cylinder 32 by a conduit 39, a check valve 40 and a conduit 41. The conduit 39 is connected to the annular space 35, as shown particularly in Figs. 3 and 5, by a port 42, the annular space 35 in turn having direct communication with the hydraulic cylinder 31. The conduit 41, as shown in Figs. 3 and 6, is connected to the reservoir cylinder 32 by ports 43 and 44 in member 30.

The reservoir cylinder 32 is connected at one end to the opposite end of the hydraulic cylinder 31 by a conduit 48, the conduit 48 communicating with the lower end of the reservoir cylinder 32 by port 50 in member 30, shown in Fig. 3 and being similar to the connection which is used to connect conduit 38 with cylinder 32 as shown in

Fig. 4. The conduit 48 is connected at its upper end to the hydraulic cylinder 31 by a port 51 in a cap 52, constituting a cover for the upper ends of the cylinders 31 and 32. Ports 53 and 54 in the cap 52 are connected by some suitable conduit means not shown to a source of compressed air for directing compressed air into the reservoir cylinder 32.

In the operation of the form of the invention disclosed in Figs. 3 through 6, the hydraulic system is provided with hydraulic fluid, the hydraulic cylinder 31 being filled and the reservoir cylinder 32 being filled to some suitable level such as at 55. The compressed air through the ports 53 and 54 maintains a pressure on the top of the hydraulic fluid with the result that hydraulic fluid is forced from the reservoir cylinder 32 through the ports 50 and 49, the conduit 48 and the port 51 into the top of the hydraulic cylinder 31 above the piston 33 to continuously maintain hydraulic fluid above the piston 33, notwithstanding the direction of movement thereof. When the piston 2 is pneumatically moved downwardly, the piston 33 is moved downwardly through the piston rod 34. As the piston 33 moves downwardly, hydraulic fluid from the reservoir cylinder 32 is forced by the compressed air above the hydraulic fluid in the reservoir cylinder 32 into the hydraulic cylinder 31 above the piston 33 as described. The hydraulic fluid in the cylinder 31 below the piston 33 is forced by the piston 33 through the port 36, the valve 37 and the conduit 38 into the reservoir cylinder 32. The valve 37 is adjusted to provide a flow of the hydraulic fluid therethrough which will provide a desired rate of movement of the piston 33 and thus the piston 2. At the same time, hydraulic fluid is prevented from passing through the annular space 35, the port 42, the conduits 39 and 41, and the ports 44 and 43 to the reservoir cylinder 32 by the check valve 40. Upon the return movement of the piston 33 following its reaching its lowermost position, hydraulic fluid above the piston 33 is returned through the port 51, the conduit 48 and the ports 49 and 50 to the reservoir cylinder 32. At the same time, hydraulic fluid from the reservoir cylinder 32 is conducted into the hydraulic cylinder 31, beneath the piston 33, by the ports 43 and 44, the conduit 41, the check valve 40, the conduit 39 and the port 42. Since the check valve 40 permits the free passage of fluid therethrough in this direction, the return movement of the piston 33 to its initial position will be at a rapid rate, whereas the movement of the piston 33 in feeding direction will be at a slow feeding rate due to the restricted orifice provided by the valve 37. As the member 2 is connected to the piston 33 by the connecting rod 34, the rate of movement of the piston 2 will be limited by the rate of movement of the piston 33.

During the operation of the feed control disclosed in Figs. 3 through 6, air bubbles are prevented from getting into the hydraulic fluid not only because of the packing rings 13 and 15 and the vent 18 as described in connection with the form of the invention disclosed in Figs. 1 and 2, but also because the maintenance of hydraulic fluid above the piston 33 at all times prevents the passage of air past the piston 33 into the hydraulic fluid which would occur if air were permitted directly above the piston 33. Also, the connection between the reservoir cylinder 32 and the valve 37 will be below the level 55 of the hydraulic fluid at all times, thereby preventing the drawing of air into the hydraulic fluid during return movement of the piston 33.

In Figs. 7 and 8 another form of the invention is shown. This form of the invention is similar in construction and function to the form disclosed in Figs. 1 and 2, except that whereas the form disclosed in Figs. 1 and 2 is for vertical operation, the form disclosed in Figs. 7 and 8 is for horizontal operation. The pneumatic cylinder 1, the piston 2 therein, the piston rod 3 controlled thereby, the piston 5, and the piston rod 4 connecting the piston 5 and the piston 2, together with the associated parts are the same in structure and function as disclosed in Figs. 1 and 2. Since the control disclosed in Figs. 7 and 8 is for horizontal operation, there must be provided a reservoir for maintaining the hydraulic chamber 6 filled with hydraulic fluid. This reservoir is provided by an annular reservoir cylinder 59, disposed about the hydraulic chamber 6. A cap 60 closes the outer ends of the hydraulic chamber 6 and the reservoir cylinder 59. Arranged in the wall of the hydraulic chamber 6 adjacent the cap 60 is a port 61 providing a communication between the hydraulic chamber 6 and the reservoir cylinder 59. For insuring that the hydraulic chamber 6 is maintained filled with hydraulic fluid, the cap 60 is provided with ports 62 and 63 with which a suitable connection with a source of compressed air not shown is provided. The compressed air on the top surface of the hydraulic fluid in the reservoir cylinder 59 urges the hydraulic fluid upwardly through the port 61 into the hydraulic chamber 6. It is to be understood that there is sufficient hydraulic fluid in the system and in the reservoir cylinder 59 so that the level of the hydraulic fluid in the reservoir cylinder 59 will never fall below the level of the port 61.

For by-passing hydraulic fluid between the cylindrical portion 7 of the hydraulic chamber 6 during slow feeding movement, there is provided in the end member 11, a port 64 to which is connected a valve 65, which in turn is connected by a conduit 66 to the lower portion of the reservoir cylinder 59. From the description of the previously described forms of the invention, it will be apparent that the valve 65 may be adjusted to provide a restricted orifice of such a size as to provide the desired rate of feeding movement of the piston 5 and consequently the piston 2. Also, it will be understood that the communication between the conduit 66 and the reservoir cylinder 59 should be at some point below the minimum level of the hydraulic fluid therein.

Still another form of the invention is disclosed in Figs. 9 through 12. This form of the invention is similar to the form disclosed in Figs. 3 through 6, the difference being that whereas the form of the invention disclosed in Figs. 3 through 6 is for vertical operation, the form of the invention disclosed in Figs. 8 through 12 is for horizontal operation.

The construction of the form of the invention disclosed in Figs. 9 through 12 is almost identical with that disclosed in Figs. 3 through 6, as will be observed by reference to the like reference characters. However, since the reservoir cylinder 32 is in horizontal position in the latter form of the invention, it will be necessary that the communication between the by-passing valve 37 and the reservoir cylinder 32 be made at some point below the minimum level of the hydraulic fluid therein. Accordingly, there is provided a conduit 69 providing communication between the by-pass valve 37 and the lower portion of the reservoir cylinder 32. The ports 53 and 54 in the cap 52

provide a communication, as in the case of the disclosure of Fig. 4, between a suitable source of compressed air and the reservoir cylinder 32.

The passage through which the hydraulic fluid is driven by the compressed air from the reservoir cylinder 32 to the hydraulic cylinder 31 is provided by ports 70, 71 and 72 in the cap 52 as shown in Fig. 12. The port 70 communicates directly with the reservoir cylinder 32, the port 72 communicates directly with the hydraulic cylinder 31 and the port 71 connects the ports 70 and 72. As shown in Fig. 12, the port 71 is provided by drilling in from one side of the cap 52 and the open end of the bore thus formed is closed with a plug 13.

It will be understood that the operation of the form of the invention disclosed in Figs. 9 through 12 is the same as the operation of the form of the invention disclosed in Figs. 3 through 6.

From the foregoing specification it will be apparent that the advantages for each form of the invention are present in each other form of the invention. Furthermore, it will be clear that I have produced a hydraulic feed control which has minimized the possibility of entrance of air bubbles into the hydraulic fluid and further has minimized the effect of air bubbles that do accidentally get into the hydraulic fluid, in that they are placed under high compression. The high compression reduces the size of the air bubbles, and therefore reduces to a minimum the jump in feeding occurring as the air bubbles pass through the restricted orifice.

In the forms of the invention wherein a reservoir is employed for maintaining sufficient hydraulic fluid on both sides of the piston in all positions thereof to cover the same, it will be evident that instead of employing air under pressure to direct the hydraulic fluid from the reservoir to the hydraulic cylinder, the parts may be arranged, as shown, to cause the hydraulic fluid to flow from the reservoir by gravity into the hydraulic cylinder. Should it become necessary to place the feed control in any position other than illustrated, it will be necessary to place all fluid ports entering cylinders 6 or 31 below fluid level for obvious reasons. The enlarged chamber portion 8 of the construction of Fig. 1 is in effect a form of such a reservoir. Accordingly any reference in the claims to yieldingly urging hydraulic fluid from the reservoir is intended to broadly include urging by gravity as well as compressed air. In addition it will be understood that other means for yieldably urging the hydraulic fluid from the reservoir is included.

Having thus described my invention, what I desire to secure by Letters Patent and claim is:

1. A device of the character described for controlling the rate of movement of a resiliently moved member, comprising a hydraulic cylinder, a cooperating piston arranged for movement in said cylinder, a rigid connection between said piston and said member, whereby said member moves said piston, a jacket about said cylinder defining therewith a reservoir for hydraulic fluid, hydraulic fluid passages between said cylinder and reservoir for maintaining hydraulic fluid on both sides of said piston at all positions thereof and hydraulic fluid passages for controlling the rate of movement of said piston and through it the rate of movement of said member, and means for directing the pressure of compressed air on the hydraulic fluid in said reservoir to force the hydraulic fluid into said cylinder and to maintain the hydraulic fluid in said cylinder under pres-

sure to reduce the size of air or the like bubbles therein.

2. A device of the character described for controlling the rate of movement of a resiliently moved member, comprising a hydraulic cylinder, a cooperating piston arranged for movement in said cylinder, a rigid connection between said piston and said member, whereby said member moves said piston, a jacket about said cylinder defining therewith a reservoir for hydraulic fluid, a restricted outlet from said cylinder to said reservoir for permitting the escape of hydraulic fluid moved by said piston from said cylinder, at a predetermined rate for controlling the rate of movement of said piston and through it the rate of movement of said member, means to provide from said reservoir sufficient hydraulic fluid on both sides of said piston in all positions thereof to cover the same, and means for directing the pressure of compressed air on the hydraulic fluid in said reservoir to force the hydraulic fluid into said cylinder and to maintain the hydraulic fluid in said cylinder under pressure to reduce the size of air or the like bubbles therein.
3. A device of the character described for controlling the rate of movement of a resiliently moved member, comprising a hydraulic cylinder, a cooperating piston arranged for movement in said cylinder, a rigid connection between said piston and said member, whereby said member moves said piston, a hydraulic fluid reservoir, a fluid connection between said reservoir and one end of said cylinder, means for connecting a source of compressed air to said reservoir for urging hydraulic fluid from said reservoir through said fluid connection into said cylinder, and means for permitting the escape of hydraulic fluid from the other end of said cylinder as said piston is moved toward said other end, whereby the rate of movement of said piston and through it the rate of movement of said member, is controlled by the rate of escape.

4. A device of the character described for controlling the rate of movement of a resiliently moved member, comprising a hydraulic cylinder, a cooperating piston arranged for movement in said cylinder, a rigid connection between said piston and said member, whereby said member moves said piston, an annular hydraulic fluid reservoir disposed about said cylinder, a fluid connection between said reservoir and one end of said cylinder, means for connecting a source of compressed air to the upper portion of said reservoir for urging hydraulic fluid from said reservoir through said fluid connection into said cylinder, and means for permitting the escape of hydraulic fluid from the other end of said cylinder at a predetermined rate and for returning hydraulic fluid to said other end of said cylinder as said piston is moved, whereby the rate of movement of said piston and through it the rate of movement of said member, is controlled by the rate of escape and return of said hydraulic fluid.

5. A device of the character described for controlling the rate of movement of a resiliently moved member, comprising a hydraulic cylinder, a cooperating piston arranged for movement in said cylinder, a rigid connection between said piston and said member, whereby said member moves said piston, an annular hydraulic fluid reservoir disposed about said cylinder, a fluid connection between said reservoir and one end of said cylinder, means connecting a source of compressed air to the upper portion of said reservoir

for urging hydraulic fluid from said reservoir through said fluid connection into said cylinder, a fluid connection between the other end of said cylinder and said reservoir, said fluid connection having a restricted orifice therein to limit the rate of flow of fluid therethrough, and another conduit connection between said last named end of said cylinder and said reservoir, said last named conduit connection having a check valve therein, whereby when said piston moves toward said last named end of said cylinder, hydraulic fluid flows through said restricted orifice into said reservoir and when said piston moves in the opposite direction, hydraulic fluid flows from said reservoir through said check valve into said cylinder, the rate of movement of said piston in the first direction being slow and in the second direction being rapid.

6. A device of the character described for controlling the rate of movement of a resiliently moved member, comprising a hydraulic chamber, said chamber having at one end thereof an active cylindrical portion and at the other end thereof an enlarged inactive portion, a piston arranged for movement in said chamber from said enlarged portion into said cylindrical portion and reverse, a rigid connection between said piston and said member, whereby said member moves said piston, an annular hydraulic fluid reservoir about said cylinder, the outside of said cylinder defining the inner wall of said reservoir, a fluid connection between said reservoir and said enlarged portion of said chamber for maintaining hydraulic fluid on both sides of said piston at

all positions thereof, means for yieldingly urging hydraulic fluid from said reservoir through said fluid connection into said chamber, and means for permitting the escape of hydraulic fluid from in front of said piston as it moves in said cylindrical portion, said escaping means having a restricted orifice whereby said piston may move through said enlarged portion of said chamber rapidly until it engages with said cylindrical portion and then moves slowly through said cylindrical portion as the result of the restricted orifice restricting the rate of flow of hydraulic fluid from said cylindrical portion.

7. A device of the character described for controlling the rate of movement of a resiliently moved member, comprising a hydraulic cylinder, a co-operating piston arranged for movement in said cylinder, a rigid connection between said piston and said member, whereby said member moves said piston, a reservoir for hydraulic fluid, connections effective during operation of said device between said reservoir and said cylinder for maintaining hydraulic fluid on both sides of said piston in all positions thereof, and means for directing the pressure of compressed air on the hydraulic fluid in said reservoir to force the hydraulic fluid into said cylinder and to maintain the hydraulic fluid in said cylinder under pressure to reduce the size of air or the like bubbles therein, and hydraulic fluid passages for controlling the rate of said piston and through it the rate of movement of said member.

LOYD A. WARD.
